United States Patent Office

Des. 181,957

Patented Jan. 28, 1958

181,957

WALKER

James P. Callahan, Memphis, Tenn.

Application April 11, 1956, Serial No. 41,019

Term of patent 14 years

(Cl. D83—1)

Fig. 1 is a side perspective view of a walker showing my new design; and

Fig. 2 is a rear perspective view thereof.

I claim:

The ornamental design for a walker, as shown.
